FURNACE

Frank L. Meyer, William J. Boesch, and Frank E. Mehrings, Peoria, Ill.

Application April 17, 1931. Serial No. 530,961

2 Claims. (Cl. 183—51)

This invention has reference to hot air furnaces for use in heating residences, stores and like places.

Said invention provides for a furnace arrangement wherein the air discharged into the building to be heated is both humidified and cleaned of dust and other suspended matter to the end that healthful conditions may be provided and maintained. Also, that air may be forced to the rooms to be heated through an air pressure system, and that at a predetermined temperature the power operating the system can be automatically cut off, the air then flowing by the usual "gravity" method.

While aware that these several advantages have been separately employed they have not been combined and used simultaneously, this being the design of the present system.

In addition, objects are to include with an air pressure system a structure including means for cleaning the air as it is drawn into the system prior to its delivery to the rooms to be heated, and to provide a specific arrangement of said means together with provision for withdrawal of the cleaning parts for renovating them.

Again, an object lies in introducing into a furnace between the body or heating unit, and the outer casing an intermediate baffle arrangement entirely surrounding said body by which radiation of heat usually lost through the said casing is prevented.

The appended drawings are provided as an aid to the full understanding of the invention.

Figure 1 is a side elevation of a furnace embodying our invention, parts being broken away to show construction. Figure 2 is a plan of the same with parts broken away for the same purpose. Figure 3 is a plan of part of the invention. Figure 4 is a perspective view of the air filter unit. Figures 5 and 6 are respectively a rear elevation and a sectional elevation of a frame and valves or dampers illustrated in Figures 1 and 4. Figure 7 is a rear elevation of parts shown in Figure 4, parts being removed to show interior details, and Figure 8 is a transverse section of a cleaner member and slide therefor.

The outer casing of the furnace as a whole is denoted at 1 while 2 is the usual smoke pipe, and at 3 is the usual cold air return duct. In Figures 1 and 2 there is erected at the rear of the furnace and connected with said cold air duct 3 a box or cabinet 4 into whose top opens a cold air pipe 5. And it may be stated that herein, and in the claims to follow, the cold air

duct is considered as including the portion 3 and said cabinet 4, together with said pipe 5.

Within the said box or cabinet 4 is erected a casing 6 whose rear wall may be the rear wall of said cabinet for convenience in constructing and using the structure. Said casing 6 terminates at its forward side, or that nearest the furnace, in a constricted opening created by walls 7 lying with their ends adjacent a frame 8, for example, lying within the duct 3. Erected in the frame 8 is a series of valves or dampers 9, the same being mounted for swinging movement on trunnions 10 at their upper and lower ends which are carried in said frame 8, see Figures 1, 5 and 6, the upper trunnions lying slightly forward of the position of the lower ones so that said valves will swing open by gravity to positions substantially parallel to each other and parallel to the line of air flow and in the direction of such flow through the duct. In this instance there are two valves at each side of the duct lying between its outer wall and the wall 7 of the casing 6, the combined width of such valves closing the space between the named portions when lying in the broken line position shown at the bottom of Figure 2 thereby leaving no opening through the said duct other than that between said walls 7.

Within the casing 6 is a housing 11 enclosing a fan 12, such housing being so arranged as to direct air from the fan into the duct 3 toward the furnace. The fan is mounted on a shaft 13 driven by a pulley 14 thereon and belted to a suitable motor at 15 for example. In the top of the casing is an opening 16 closed by a screen 17 in the form of a slide removable through the rear wall of the box 4, a convenient handle 18 being provided for the purpose. The casing is closed at its top except for said opening 16, and its sides are flared, in this instance, being directed outwardly and rearwardly toward the corners of the box and each flaring portion has an opening 19 closed by a screen 20 slidably mounted and withdrawable through the wall of said box, a suitable handle 21 being supplied as in the other instance. Except for the screened openings mentioned, the interior of the casing is entirely cut off from that part of the duct within the box 4, the purpose of which will become evident as the description proceeds. The manner of mounting and guiding the several screens 17, 20 is suggested in Figure 8 wherein a channel member 20' acts as a guide for a screen, this being shown, as to position, in Figure 7, and it may be stated that said screens may be made in

any desired manner and may contain a material such as fiber or other substance that may be kept moistened in any desired way, not shown, or it may be treated with an oil with the purpose 5 of catching and retaining dust and other suspended matter carried in the air-stream. As arranged, it is the purpose that the fan 12 will operate automatically through a suitable switch, not shown, controlled by suitable means including 10 a thermostat located at a desired point, as 22 in Figures 1 and 9.

In practice, the fan assists in circulating the air in the rooms being heated by forcing to the latter the heated air within the furnace casing 15 that might be more or less static, depending upon conditions, and serves to maintain a more equable condition of the furnace-body by preventing too great extremes in expansion and contraction thereof, prolonging its usefulness, besides making 20 better use of all of the created heat.

Though not shown, the usual thermostat is employed in the rooms by which to cause the operation of the furnace dampers in a customary way, the thermostat 22 operating separately 25 therefrom, being affected only by the temperatures of the furnace casing.

As the room temperature rises above a predetermined point due to open dampers at the furnace the thermostat 22 by reason of increased 30 casing-temperature sets the motor 15 in action so that the heat built up within said casing is forced to the rooms, fulfilling the above purposes, it being thus seen that the operation of the fan must always follow that of the drafts, and continues in operation during an interval thereafter 35 or as long as the furnace gives off sufficient heat to hold said thermostat 22 at a given high point. Contrarywise, as the furnace-heat falls the fan will cease to function. However, the intervals of 40 rest of the fan may be comparatively short, being governed primarily by the periodic action of the room thermostat. It is quite evident that the fan will never be in operation when the temperature within the casing is below a point where the air 45 may be what may be termed "cool". When the fan is idle the air from the rooms flows by gravity through the box 4 the space between past the valves 9 to the furnace, said valves at such times standing open as shown in Figure 2. However, 50 when the fan is in operation, and the air is forced into the duct 3 beyond the valves, static pressure is set up whereupon said valves automatically close, being held in that position by such pressure, or as long as the fan is in operation. 55 During such period no air can pass to the furnace except through said fan and the opening of the casing 6 described. The air entering the box 4 through the intake pipe 5 must now all pass 60 through the screens 17, 20 and thereby must be cleaned of suspended matter, passing to and through the furnace and into the rooms in a pure state. When the room temperature is sufficiently high the motor 15 continues in action after the

furnace dampers are closed, as already intimated, its action terminating only when the furnace temperature has dropped below a given point as set by the thermostat 22. Thereupon, the static pressure ahead of the valves being relieved said valves 80 open by gravity, the air travel being by gravity flow between the valves as explained. And while the bulk of air will travel through the path of least resistance some of it may move through the screens, depending, of course, upon the resistance 85 set up thereby.

The furnace is provided with any usual water container, as 23, for example, by which the air is kept humidified, which, together with the cleaning of the air, provides healthful conditions while 90 more uniform temperatures are maintained.

We claim:

1. In a structure for use in conditioning air, the combination of an air conducting pipe, a casing enclosed in said pipe, one side of said casing being closed by one of the walls of the pipe, certain of the casing walls being spaced from the other walls of said pipe thereby providing for an air space within the pipe around the named casing walls, the thus spaced walls of the 100 casing each having an opening therein for communication of air in the space of the pipe with that of the casing, there being openings in the walls of the pipe opposite the openings of the casing walls, and a filtering member insertable in 105 each of the openings of the pipe to overlie the openings in the casing walls, there being an outlet in one of the walls of the casing for the passage of air therefrom, said air passing from the pipe through said filtering members into the casing 110 and thence to said outlet.

2. In a structure for use in conditioning air, in combination, an air conducting pipe, a casing erected therein, the pipe and casing having separate non-communicating outlets for the delivery 115 of air independently of each other, the casing at one side abutting a wall of the pipe and having walls spaced from the other walls of said pipe, said casing having a top wall including therein an opening lying adjacent the first named wall, 120 there being an opening in said first named wall adjacent the named opening of the said top wall of the casing and communicating with the passage of the pipe, two opposite walls of the casing each having an opening therein, a filter 125 member insertable through the pipe wall into each of the named openings and each separately covering an opening, the several filter members being exposed to the space of said pipe, air moving through the pipe being free to enter the casing 130 through the filter members, while free also to pass out of said pipe through the outlet thereof around and independent of said filter members and the casing.
